Primary Examiner — Marianne Pandozzi(74) *Attorney, Agent, or Firm* — Knobbe, Martens, Olson & Bear LLP**(57) CLAIM**

The ornamental design for a plug for beverage container lid, as shown and described.

DESCRIPTION

FIG. 1 is a perspective view of a plug for beverage container lid configured in accordance with the present invention;

FIG. 2 is a front view thereof;

FIG. 3 is a left side view thereof;

FIG. 4 is a rear view thereof;

FIG. 5 is a right side view thereof;

FIG. 6 is a bottom view thereof; and,

FIG. 7 is a top view thereof.

The broken lines in the drawings are included for the purpose of illustration and form no part of the claimed design.
